UNITED STATES PATENT OFFICE.

EDWARD NUGENT, OF BROOKLYN, NEW YORK.

IMPROVEMENT IN MACHINES FOR MAKING BULLETS, &c.

Specification forming part of Letters Patent No. 22,974, dated February 15, 1859.

To all whom it may concern:

Be it known that I, EDWARD NUGENT, of Brooklyn, in the county of Kings and State of New York, have invented a new and Improved Machine for Casting Buckshot, Balls, and other Small Projectiles; and I hereby declare that the following is a full, clear, and exact description of the same, reference being had to the accompanying drawings, forming part of this specification, and to the letters of reference denoted thereon, in which—

Figure 1 is a horizontal section on the line S S in Fig. 2. Fig. 2 is a vertical section on the line S S in Fig. 1. Fig. 3 is a diagram showing the motion of a portion. Fig. 4 is a section of a portion, full size. Fig. 5 is a corresponding section on a line at right angles to the last. Fig. 6 is a longitudinal section of the cylinder F alone. Fig. 7 is a view of one of the links R, and Fig. 8 is a diagram showing the relative positions of some of the parts.

Similar letters of reference indicate like parts in all the drawings.

The object of my invention is to provide means of casting and cooling small projectiles more rapidly and with less labor than heretofore. It consists in making the cavities in which the shot are cast in the sides of thin rings, the peripheries of which work in tight contact with a mouth in the side of the kettle or reservoir of melted metal, the lead in the kettle pressing constantly against the peripheries of the rings, and each cavity being filled as its passes the open mouth or slot, no superfluous metal being allowed to escape.

In connection therewith my invention also consists in the use of a screw or its equivalent revolved within a suitable case connected to the mouth, so as to drive the fluid metal downward toward the mouth, whereby the pressure of the lead at the mouth is increased, and, while rendered in the main more uniform, the particles are agitated and the pressure rendered slightly concussive, as will be explained below.

It likewise also consists in applying cold water to the inner surfaces of the cylinder on which the rings are sustained, the cylinder being hollow and cold water being made to circulate freely within it, by which means the balls are rapidly cooled and made fit to be discharged.

It further consists in giving an endwise or axial movement to the rings, and imparting thereto such motions that while some of the rings tightly pressed together are being presented to the melted metal and filled others are made to separate to a sufficient distance to allow the shot to leave the cavities, after which the last-described rings again come together and are presented to the mouth to be filled, while the first-named rings discharge their shot in a similar manner.

It further consists in a peculiar means of opening and closing the rings, whereby they are shaken or jarred when fully open, so as more certainly to let fall the shot contained in the cavities, and also whereby they are yieldingly pressed together, so as not to allow the possible catching of a shot between the plane surfaces of the rings—serious danger to the mechanism.

To enable others skilled in the art to make and use my invention, I will proceed to describe its construction and operation.

A is the main kettle or reservoir in which the lead is melted. B is a hollow cylinder contained within the first. C is an opening through which metal can flow from A into B. D is a mouth through which, when unobstructed by any object outside, the metal may flow freely from B. E E', &c., are thin rings, containing in their sides semi-spherical cavities e e. F is a thin cylinder, which is caused to rotate slowly by any convenient power. The trunnions or bearings G G' are hollow, and cold water, air, or other fluid is caused to enter through one trunnion, G, and allowed to escape more or less warm at the opposite trunnion, thereby conveying away the heat imparted to the cylinder by the hardening of the shot within the mold.

The mold-rings are attached to the thin cylinder F by feathers in such manner, as will be more fully described below, that they are free to move endwise on F, but are compelled to rotate with the slow revolution thereof. There are two series of rings E, one denoted by E and the other denoted by E'. (See Fig. 1.) These rings and the cylinder are made to operate in a peculiar manner, which will be now fully explained. In Fig. 1 the rings E are in close contact each with its mate, and are revolved in such position that the lead in D

fills and cuts the several molds *e* as they are successively presented. The mouth *D* is so accurately shaped that it fits tightly to the surfaces of the rings *E*, and allows no escape of the melted metal except into the cavities *e e*, which are completely filled as they are successively presented, the sprue of each shot being cleanly and smoothly cut as the rotation slides it away from the mouth *D*. The mold-rings *E* are in a very different condition, they being entirely removed from the mouth *D* and separated to a sufficient distance each from its mate to allow the free escape of the shot which has been previously molded in the cavities *e* between them. When by the rotation of the cylinder *F* all or nearly all of the cavities between the mold-rings *E* are filled with metal, the mold-rings *E* are brought together, the cylinder *F* is moved rapidly endwise on the trunnions *G*, and thus the rings *E'* are presented to the mouth *D*, while the mold-rings *E* are removed from *D* and are separated each from the other. When the cavities between *E* are supplied and those between *E'* emptied, the parts again assume the position shown in Fig. 1. The means by which I produce these motions is as follows: The extreme or outer rings of the two series *E E'* are grooved, as represented in Fig. 1. In these grooves stand the extremities of arms *H H'*. The arms, *H*, are fixed on the slide *I*, and the corresponding arms, *H'*, are fixed on the slide *I'*. Both the slides *I I'* are so mounted on the side of the horizontal bar *J* that they are free to slide endwise thereon to a limited extent, they being severally connected thereto by pins *i*, which are fixed in *J*, but which are merely embraced in slots in *I*, as represented in Figs 2 and 3. The horizontal bar *J* is loosely supported upon a fixed framing, *K K*, so that it is free to move endwise. The rotary motion of *F* is derived from the vertical shaft *L*, which is driven by a steam-engine or other power and impels by means of a worm, *M*, and wheel *N*. (See Fig. 1.) The wheel *N* is secured on the trunnions *G* by a feather and spline, (not represented,) so as to allow for the end motion of *G* through it. *N* takes hold of the fixed frame *K* by the collar represented, so that it is not capable of moving endwise. A cam-wheel, *O*, is fixed on the side of *N*. Its periphery is grooved as represented, and a swiveling piece, *j*, on the side of *J* stands in the groove.

The operation of these portions of the mechanism is as follows: The revolution of *L* imparts a slower rotary motion to *N O*. The form of the groove in *O* compels *J* to remain at one extreme of its motion till *N O*, and consequently *F*, has nearly completed a revolution, when it is moved by the cam *O* nearly or quite to the opposite extreme of its travel. This movement of *J* is communicated by the pins *i i* to the slides *I I'*, and thus through the arms *H* to the two grooved mold-rings *E E'*, the outermost of the series.

There now remains to be described other

important portions of the mechanism as follows: There are two tumbling bars, *P P'*, hinged at their lower extremities to fixed points, as represented, and carrying heavy weights *Q Q'* at their upper ends. These tumbling bars are connected to the loose slides *I I'* by the pins *p p*, as represented, and the parts are so proportioned—as may readily be done by any good mechanic—that when by the action of the cam *O* the bar *J* commences to slide endwise it first tumbles one of the tumbling bars and then the other, the one first tumbled being the one which closes the empty series of mold-rings and moves the cylinder endwise to present them to the mouth *D*, and the one last tumbled being the one which opens the filled rings to discharge the shot. The relative inclination of the two tumbling bars in order to effect this is shown in outline in Fig. 8. The surface of the cylinder *F* is grooved or splined longitudinally along four or more lines, the cylinder being thicker at those parts to allow therefor, as shown in Figs. 2 and 4. In these grooves are placed short open links *R*. (Shown separately in Fig. 7.) The thickness of these links is somewhat greater than the depth of the grooves, and a corresponding groove is made in the inner side of the mold-rings, whereby the links are made to serve as keys or feathers to compel the rings to rotate with *F*. Another and chief function of these links is to loosely connect the several rings, which is effected by the aid of pins *r r*, fixed in the inner surface of the rings and extending into the links. Each ring *E* or *E'* has as many pins *r r* as there are grooves in the cylinder *F*, and each alternate pin connects by a link, *R*, to its neighboring ring on the right side, while the remainder connect in a similar manner to the ring on its other or left hand. These pins *r* are of no effect when the rings are in the position of the rings *E* in Fig. 1; but they are very important when the rings are separated, like *E'* in the same figure. In the latter position they serve to prevent the rings from separating too widely either from each other or from the fast ring *F'*, which latter ring is fixed on the cylinder *F* between the series *E* and the series *E'*, and to which both series are connected.

Commencing with the parts in the positions shown in Fig. 1, the complete operation of the mechanism is as follows: When by the action of the cam *O* the bar *J* moves endwise, it first moves idly while the pins *j j* traverse the corresponding slots in the slides *I I'*. Continuing its end motion, it moves the slide *I'*, and with it the bar *P'*, lifting the weight *Q'* through the arc from 1 to 2. (See Fig. 3.) On moving a little farther the gravity of *Q'* assists the motion of the slide *I'* and carries it rapidly and with some violence to the extreme of its motion. In performing this movement the slide *I'*, by means of the two arms *H'*, produces the following effects, viz: First, it presses into contact with each other all the rings in the series *E'*, and, second, by the

pressure of these rings against F it moves the cylinder F endwise to the full extent to which it is allowed to travel, its motion being gaged in any ordinary manner. (Not represented.) This operation completely removes the rings E from the mouth D and substitutes the rings E' in their place. Subsequently the continued end motion of J moves the slide I to a sufficient extent to tumble the bar P, which causes it to hasten the motion of I, and by the aid of the arms H to separate the several rings in the series E to the full extent allowed by the links and pins R r, the several rings being sensibly jarred or shaken by the suddenness with which this opening is effected. The sliding bar J and all its connections now remain quiet, while the cylinder F makes a nearly complete revolution, after which the reverse motion of J produces a similar effect, first closing the intervals between the rings E and moving the cylinder F endwise, and then, either immediately or after a short interval, opening the spaces between the rings E. The dotted lines on the cam O show the form of cam which will cause the opening of the rings to be delayed for a considerable interval after they have been removed from the mouth D. A considerable pressure and a slight jarring motion of the melted lead at the mouth D appears to be important to the complete and certain filling of the cavities e e. The pressure cannot be increased by elevating the kettle, because the lead congeals in the conveying-pipes, and any ordinary pump causes too unsteady and yet too gentle an agitation. In my invention I produce a proper increase of pressure and at the same time a proper agitation of the fluid by the rotation of the broad

thin screw T within the cylinder B, as represented. The cylinder B, above and below the screw T, may, if preferred, be fitted with a fixed spiral or thread the reverse of the screw T, in order to increase the effect of T by well-known laws; but I do not consider it necessary.

By the invention above described I am enabled to manufacture buckshot, balls, rifle-projectiles, and the like much more rapidly and with less labor than by any means previously known. It also involves less exposure of the melted metal to the atmosphere, and consequently produces less oxidation and waste of metal.

Having now fully described my invention and its operation, what I claim as new in the manufacture of buckshot and balls, and desire to secure by Letters Patent, is—

1. The revolving self-cutting mold E E', working in contact with the mouth D of the lead-kettle through which the cavities e e are supplied with metal, substantially in the manner and for the purposes above set forth.

2. The end motion of the two series of mold-rings E E' and the opening and closing of the several rings in one series while the cavities in the other series are being filled, substantially as above set forth.

3. The tumbling bars or their equivalents, operating substantially as described, by which a concussion is produced when the mold-rings are opened and allowance is made for any obstruction between the rings when closed, as within set forth.

EDWARD NUGENT.
